CLAIM

The ornamental design for a charcoal fuel article or similar article, as shown and described.

DESCRIPTION

FIG. 1 is a top plan view of a charcoal fuel article or similar article showing my new design, the bottom plan view being a mirror image;

FIG. 2 is a top and side perspective view thereof, all sides being the same.

U.S. Patent

Nov. 14, 1989

D304,574

FIG. 1

FIG. 2
